UNITED STATES PATENT OFFICE

2,500,463

TISSUE DISPENSER COMBINED WITH
FLUSH TANK

Burton H. Locke, Framingham, Mass.

Application April 4, 1947, Serial No. 739,307

5 Claims. (Cl. 4—68)

1

My invention relates to an improvement in flush tanks for closets which affords a utility feature as a component part thereof and thereby eliminates one of the several devices that are necessary in a bath room. The objects of the invention are to provide a place to house rolled toilet tissue that will conserve the space generally required for suspending same on the wall, as is common practice heretofore, and to achieve a sanitary condition by completely enclosing the roll of tissue. Another object is to afford a means whereby the tissue can be readily sheared from the roll without the roll unwinding and thereby dispensing excessive tissue. It appears obvious that a roll of tissue can be housed in a conventional flush tank by the addition of a separate water-tight compartment therein without substantially changing the size or shape of same. Also, it is well known that flush tanks are generally positioned in the back of the closet, as shown in the accompanying drawing, which positions same desirably to house the roll of tissue. Having conceived these facts and having the objectives set forth in my application for improvement in Dispensers for rolled paper, filed March 14, 1947, Serial No. 734,706, now abandoned, in mind, I conceive the invention set forth in the following specifications:

In the accompanying drawing:

Figure 1 is a side elevation of a conventional flush tank with cover in its general relative location to a closet and shows my improvement when applied to the flush tank cover.

Figure 2 is a front elevation of same.

Figure 3 is a top view showing the flush tank of Figure 1.

Figure 4 is a side elevation similar to Figure 1 showing my improvement when applied to the flush tank.

Figure 5 is an enlarged section showing the dispenser unit as it would appear when arranged in the flush tank cover to support the roll of tissue axially on a spindle.

My improvement in flush tanks for closets comprises the addition of a compartment 10, either in the tank cover 11 as best shown by Figure 1, or in the tank 12 as shown by Figure 4. Compartment 10 is suitable to house a roll of toilet tissue 13 which is preferably supported at its periphery by the housing, although same could be supported by a spindle 14 that could be slid through the roll of tissue 13 and then dropped into U guides 15, or other suitable supports, that are fastened to, or made integral with, the sides 16, of compartment 10, all as shown by Figure 5.

2

Obviously, compartment 10 would be immured from the water A that flows through the tank and would be positioned to eliminate interference with the conventional operating mechanism of the tank, such as the float 17 shown, and the float valve; stand pipe; operating levers and linkage etc. which are deemed unnecessary to be shown in the drawing. Whether the compartment 10 is located in the tank cover 11, or in the tank 12, the essential details are substantially the same. There is an opening 18, into compartment 10, to permit the insertion of the roll of tissue 13 and a cover 19, either being loose, or hinged in some convenient manner to the flush tank or its cover, as the case may warrant, as shown by 20. There is a slot 21 formed, in this instance, by the joining of the cover 19 and its cooperating seat 22, and the outer edge 23 thereof is suitably constructed to shear the tissue thereon. In the instance shown, a blade 24, with a serrated edge 25, is attached to seat 22 in some conventional manner to form shearing edge 23. However, when practical the blade 24 could be eliminated and a suitable shearing edge could be formed integrally on seat 22. The shearing edge 23 is a distance outside of compartment 10 so that the free end of the tissue will be left protruding outside the compartment, after same is sheared, for the user to grasp at subsequent times. Cover 19 is notched out at 26 to permit the user to place thumb or finger onto the end of the tissue for dispensing same from the compartment.

Flush tanks are generally located on the wall in back of, and slightly above, the closet 27, substantially as shown by Figures 1 and 2, and would thus serve as a convenient place for the roll of tissue to be housed. A quick tug on the dispensed end of the tissue as shown at B causes the tissue to be sheared on edge 23 without further unwinding of the tissue roll which insures against excessive tissue being dispensed. When compartment 10 is located at the bottom of the flush tank as shown by Figure 4, some conventional means, such as bolt 28, is required to hold cover 19a up into position to support the roll of tissue. However, in this instance cover 19a could be eliminated if the roll of tissue was supported on a spindle similar to that shown by Figure 5, by sacrificing the sanitary feature set forth.

Although it appears that either the arrangement shown by Figure 1 or by Figure 5 is the preferred construction, I do not wish to be confined to any exact details as same are susceptible of modification without departing from the spirit

or scope of the invention as broadly set forth in the claims to follow.

I claim:

1. A flush tank cover comprising a dome shaped structure having a continuous wall substantially covering the said tank, a depression in said wall extending down into the flush tank to utilize the normal space intermediate the float valve mechanism normally in said tank and the top of said tank, said depression being suitable to receive and house a roll of toilet tissue immuned from the water normally flowing through the said tank, a slot for dispensing the tissue to the front of the tank, a movable cover for said depression to complete the enclosure of the roll of tissue, a projecting portion at said slot with the outer edge thereof being adapted to sever the tissue thereon.

2. The combination of an open top flush tank and removable cover therefor, the tank having conventional float valve and operating mechanism, the cover comprising a dome shaped structure having a continuous wall to substantially cover the said tank, a depression in said wall extending down into the flush tank to utilize the normal space intermediate the normal float valve mechanism in said tank and the top of said tank, said depression being suitable to receive and house a roll of toilet tissue immuned from the water normally flowing through the said tank, a slot for dispensing the tissue to the front of the tank, a movable cover for said depression to complete the enclosure of the roll of tissue, a projecting portion at said slot with the outer edge thereof being adapted to sever the tissue thereon.

3. A flush tank having conventional float valve and operating mechanism, a depression in said tank to receive and house a roll of toilet tissue immuned from the water normally flowing through

the tank, enclosure means for said depression to complete the enclosure of the roll of tissue, a slot formed by the joining of the enclosure means and the edge of said depression for dispensing the tissue to the front of the tank, an edge at said slot suitably adapted to sever the tissue thereon.

4. The combination of an open top flush tank and a removable cover therefor, the tank having flush valve with operating mechanism therefor, the cover having a cavity extending down into the said tank, said cavity being watertight, in respect to the normal flow of water through the tank and being suitable to house a roll of toilet tissue immuned from the said water, a slot for dispensing the tissue to the front of the tank, a cover for the said depression to complete an enclosure of the roll of tissue, means for severing the tissue from the roll after being dispensed through the said slot.

5. A flush tank cover having a cavity that will extend down into a flush tank and being suitable to house a roll of toilet tissue immuned from the water that normally flows through the tank, a cover for the said cavity to complete a housing of the roll of tissue, a slot to permit the dispensing of the tissue to the normal front side of the tank cover.
